No. 703,877.

Patented July 1, 1902.

B. WOLVERTON.

HINGED GATE.

(Application filed Feb. 6, 1902.)

(No Model.)

UNITED STATES PATENT OFFICE.

BRUCE WOLVERTON, OF PORTLAND, OREGON.

HINGED GATE.

SPECIFICATION forming part of Letters Patent No. 703,877, dated July 1, 1902.

Application filed February 6, 1902. Serial No. 92,801. (No model.)

To all whom it may concern:

Be it known that I, BRUCE WOLVERTON, residing at Portland, in the county of Multnomah and State of Oregon, have invented certain new and useful Improvements in Hinged Gates, of which the following is a specification.

My invention relates to improvements in that class of farm-gates having means at one or both sides thereof for opening the said gate; and it comprehends a novel correlation of parts, including a foldable combined brace and pull member and a novel arrangement of latch-bar coöperatively joined with the said foldable brace and a supplemental means for tripping the said brace, all of which will hereinafter be first described in detail and then be specifically pointed out in the appended claims, reference being had to the accompanying drawings, in which—

Figure 1 is a perspective view illustrating my improved farm-gate in its closed position. Fig. 2 is a diagrammatic view showing the same in its opened position in dotted lines. Figs. 3 and 4 are detail views illustrating the hinge end of the foldable arm and the hinge-post to which it is secured. Fig. 5 is a detail view of the bracket-piece *d*. Fig. 6 is a detail view of one of the eye members for supporting the gate. Fig. 7 is a detail view showing the hinge connection of the two members of the foldable arm hereinafter referred to, and Figs. 8 and 9 are detail views illustrating the modified construction of the said foldable arms.

Referring now to the accompanying drawings, in which like numerals and letters indicate like parts in all the figures, *A* designates what I term a "foldable combined brace and pull member," consisting of an inner and an outer part *a a'*, the inner one of which has a strap-plate *a²*, the lower end of which is turned up to engage the pintle *a³* on the bracket-piece *d*, mounted on the upper end of the short post *c*, disposed at one side of the gate, as clearly shown in Fig. 1.

The two members *a a'* are hinged to fold flatwise upon each other, the hinge member being indicated by *h*, and to hold the two members *a a'* from lateral strain and a consequent wear on the hinge *h* the said members *a a'* have blocks *x x'*, one of which has

a V-seat and the other a V projection to engage the said seat, as clearly shown in Fig. 7.

To provide for the foldable member *A* projecting properly relatively to the gate, the hinge end is beveled at a proper angle, as shown, and the several portions of the member *A* are set in such relation and on such bevel or angle to the gate as to permit the two portions constituting the said member *A* when the gate is opened to fold flatwise upon each other and at right angles to the gate, as clearly shown in Fig. 2. The relation of the said member *A* to the gate is also such as to allow the foldable member *A* to rise nearly to a perpendicular position as the gate closes.

The front end of the member *A* is attached by an iron loop *e* to the gate by means of a double crank-rod *f*, disposed vertically and having its crank member *f²* connected with a sliding latch *g*, the two crank members and the member *a'* being so disposed that as the member *a'* is pulled back the double crank *f* will be moved to cause the latch member *g* to pull back and disengage the latch-post *L*, the parts being so arranged that the double crank member will be turned the distance of sixty to ninety degrees, it being understood that when the gate is closed and the members *a a'* assume a straight position a reverse action is imparted to the double crank member and the latch *g* moved forward to hold the gate closed.

Instead of forming the members *a a'* of two flat wooden members, as shown in Fig. 1, the said foldable member *A* may be constructed of two iron-bar sections, as clearly shown in Figs. 8 and 9, both of which terminate in broadened ends adapted to form a hinge connection with each other by means of the hinge-pintle *11*, and one of the said rods is provided with a hook *12*, adapted when the two rods are extended in the same plane to engage an aperture *12^a* in the other member, whereby to lock the said rod members in their proper adjusted position, it being understood that when the continuity of the foldable member is broken the said hook *12* will automatically move out of engagement with the aperture *12^a*.

The hinge member of the gate *G* is provided with an ordinary staple or hook member *15*, adapted to seat in the staple *16*; but the up-

per end of said member has a vertically-projecting hook member 17, movable within the segmental slot n , formed in the end of the bolt N , made fast to the post P , as shown.

5 The object in providing this form of hinge connection for the gate is to throw the gate from an upright position when it is opened to assist the opening thereof, and by a similar movement contrawise exerted the weight 10 of the gate will assist in closing.

K designates an eye projected up from the member a' near its hinged end, the purpose of which is to receive a cord or wire, which runs over a swivel-pulley l , suspended from 15 a bar fixedly held on the post P and projected in a plane at right angles to the gate when closed, said pulley being a double one, whereby the ends of the cord R are passed in opposite directions, each end passing over another pulley S on a post T at one side of the gate and having a pull R' , as shown.

The manner in which my improved gate is operated is best explained as follows: Assuming the gate to be closed, to open the same it is 20 only necessary to pull upon the cord R from either end, which causes the foldable arm to rise to a vertical position and at the same time to operate the double crank, unlatch the gate, and pull the gate back from engagement with the latch-post. This movement causes the gate to swing outward in the direction of the post c to the position shown in Fig. 2. The same operation of opening the gate may be accomplished from the inside by 25 the supplemental device, which consists of a lever Q , suspended in the hanger p , and provided with a U-hook Q' , projected under the upper arm a' of the member A . This supplemental device is intended for the convenience of footmen coming from the side opposite that on which the foldable member A is placed.

By reason of the peculiar correlation of the parts described and shown they provide for 30 easily and conveniently opening and closing the gate, such action being made effective first by the manner in which the gate is hinged on the post P , the eye and slot allowing the

gate to be thrown out of plumb, the momentum of the gate and the weight thereof relieving the operator from any undue strain in opening the gate. 50

By reason of the peculiar manner in which the member A is attached to the gate it is made possible to unlatch the gate and swing it open with but a single movement. 55

Having thus described my invention, what I claim, and desire to secure by Letters Patent, is—

1. The combination with the hinged gate, 60 and the foldable member A , disposed at an acute angle to the hinged end of the gate, and hinged at its lower end to swing upward; of the sliding latch g , and the double crank e , connected to the latch and the upper end of member A , substantially as shown and described. 65

2. The combination with the hinged gate, the post c , and the foldable member A , hinged to post c , and arranged substantially as described; of the latch g , the double crank e , arranged in a vertical plane and having one member connected to the inner end of the latch and the other member connected to the outer end of the foldable member A , all being arranged substantially as shown and described. 75

3. The hereinbefore - described improved gate, comprising a gate hinged to tilt its upper part sidewise while moving to an open 80 position, a foldable lever hinged at its outer end to project at an acute angle to the hinged end of the gate, said lever consisting of two sections a' , the latter being hinged to fold flatwise on the former, the double crank e 85 having one member adapted to join with the outer end of lever-section a' , the sliding latch g , with its inner end connected to the other crank member, the pivoted lever q , the pull-ropes and the guides therefor, all being arranged substantially as shown and described. 90

BRUCE WOLVERTON.
